UNITED STATES PATENT OFFICE

2,418,807

RACE STARTING GATE

Jesse P. Whann and Norman C. Harris, Los Angeles, Calif., assignors to Puett Electrical Starting Gate Corporation, Beverly Hills, Calif., a corporation of California

Application September 9, 1941, Serial No. 410,142

11 Claims. (Cl. 119—15.5)

1

Our invention relates to improvements in starting gates such as used at race tracks to start animals in races and relates in particular to a starting gate device wherein all of the individual gate elements are held in closed relation by releasable latch means adapted for simultaneous operation to instantly and simultaneously open all of the gates, thereby giving all of the racing animals opportunity for an even start.

The present invention is a continuation in part of the application which became Patent No. 2,309,952, February 2, 1943.

It is an object of the invention to provide a starting gate construction where the gates are all held so that possibility of failure to open is substantially avoided. Our present starting gate is an important improvement over starting gate devices having the ordinary forms of mechanical latches. The mechanical latch devices employed in the past for holding the starting gates in closed position have some times failed as the result of the sticking of a latch having frictionally engaging parts. A single failure of a starting gate causes considerable confusion and obviously spoils the race improperly started by failure of the mechanism.

It is an object of the invention to provide a starting gate having gate means for closing the forward end of the starting stall, with a latch for holding the gate means in closed position, such latch comprising two engageable parts which accomplish their latching effect by engagement of cooperating shoulders, at least one of the engageable parts being magnetically held in operative position in such manner that release of the magnetism results in a free movement of the part so held to a latch releasing position. Accordingly, the release of the latch is accomplished not by movement of two frictionally engaged shoulders or faces out of overlapping engagement, but by a free movement of at least one of the latch members due to gravity, and as explained hereinafter in the specification, from the operative position in which it is held by magnetism.

A further object of the invention is to provide a starting gate structure having latch means wherein one of the latch elements is characterized by yieldability in a vertical direction so that when the gate means is moved into closed position, the cooperating engagement parts of the latch will pass by each other to the extent of moving portions of the engagement members into overlapping relation whereby the latching shoulders thereof may engage. According to the in-

vention one of the engagement members is supported so that it may be moved from a releasing position to an operative position and there held by an electromagnet cooperating in such a manner that the only force holding the engagement member in operative position is the force of magnetism which passes from the electromagnet through an armature or keeper forming part of the movable engagement member. However, it is not necessary to adjust the gate means into closed position and then move the cooperating engagement members of the latch into holding position, but when the electric current of the system is turned on, the magnetically held engagement member will be moved by magnetism into its operative position. Thereafter, closing of the gate means results in latching of the engagement members of the latch, one of these engagement elements being characterized by yieldability which will permit the latching engagement. By "characterized by yieldability" we mean that the engagement member so characterized may yield bodily or may have a part thereof which is yieldable for the purpose of accomplishing the result specified.

In the practice of the invention the gate means may consist of two gate elements adapted to be swung from open position to a position in which edges thereof will meet, and the latch means may be positioned so that one of the engagement members will be on one of the gate elements and the other of the engagement members will be on the other gate element.

35 A further object of the invention is to provide a starting gate device having gate means and non-sticking latch means for holding the gate means in closed position, such latch means having one part thereof on the gate means and the other part thereof on the frame structure of the starting gate device.

40 A further object of the invention is to provide a starting gate device having a pair of gate elements to close each starting stall of the device, and non-sticking latch means for the gates cooperating between the gate elements and the frame or supporting structure so that the gate elements may be separately and individually latched in closed position merely by swinging them from open position toward closed position as far as they will go, there being no care required in the bringing of the meeting edges of the gate element into a prescribed cooperative relation.

45 Further objects and advantages of the inven-

tion will be brought out in the following part of the specification.

Referring to the drawings which are for illustrative purposes only:

Fig. 1 is a face view of a starting gate embodying our invention, with a central portion of the starting gate structure removed, and with the closures or gate elements shown in both closed and opened positions.

Fig. 2 is a plan sectional view, the parts in section being taken on line 2—2 of Fig. 1.

Fig. 3 is an enlarged sectional view taken as indicated by the line 3—3 of Fig. 2.

Fig. 4 is a fragmentary plan view corresponding to Fig. 3.

Fig. 5 is a fragmentary perspective view of the upper part of a starting stall, to show an alternative form of the invention.

Fig. 6 is an enlarged fragmentary sectional view taken as indicated by the line 6—6 of Fig. 5.

Fig. 7 is an enlarged fragmentary section taken as indicated by the line 7—7 of Fig. 5.

Fig. 8 is a fragmentary elevational view showing the manner in which a form of our improved latch may be mounted on the meeting vertical edges of two cooperating starting gates.

The starting gate device 10 shown in Figs. 1 and 2 comprises a framework or structure 11 which may be made up of welded tubular parts. This structure 11 has pairs of wheels 12 at the ends thereof whereby it may be rolled on and off of the track. The structure 11 provides a plurality of stalls 13 defined by padded substantially parallel partitions or walls 14. The term "framework" in the claims includes all of the stationary parts of the starting gate. The framework therefor includes the overhead structure 11, the stanchions or the vertical supports forming part of the partitions, in fact this term is used to distinguish the swinging doors from the other parts of the gate, the doors being the movable parts and the remainder of the gate being the stationary part.

To close or obstruct the forward portions of the stalls 13, gate means 15 are provided, such gate means preferably comprising a pair of gates or closures 16 hinged on vertical axes or pivots so that they will be swingable between an open position 16a in which they are substantially parallel as best shown in Fig. 2, and a closed position 16b wherein their side edges farthest from their vertical pivots are adjacent to each other. Whether the closures lie in diagonal planes or are at an angle of 180° to each other is a matter of choice as both arrangements are well known in this art as is illustrated in the hereinafter referred to Puett et al. patent, and the patent to Comfort et al. No. 1,870,768, dated August 9, 1932, and the Macksoud Patent No. 2,319,420, May 8, 1943 (Figures 4 and 5).

As shown in Fig. 1, the gates or closures 16 may be fabricated from steel tubing, with a tube or bar 18 disposed vertically at the outer edge thereof to provide a shaft or axle element engageable by bearings 19 in which the gates 16 may be swung between opened and closed positions. The lower portion of each gate 16 may carry an opaque padded wall 20, and above the wall 20, a screen 21 may be disposed in the gate substantially in alignment with the heads of the horses and the jockeys. On a lateral frame member 22 extending above the forward portions of the stalls 13 there are latch means 23, preferably arranged on the central vertical planes

of the stalls 13. Each gate 16 has a structural part 24 thereof carrying an engagement member 25, and the structural parts 24 and the engagement members 25 are so positioned that when the gates 16 are swung from open position 16a to closed position 16b, the structural parts 24 will carry the engagement members 25 into latched engagement with cooperating parts of the latch means 23 in the manner hereinafter described relative to Figs. 3 and 4. The structural parts 24 may be arms bent laterally or extending laterally from the upper ends of the shaft portions 18 of the gates 16, in such angular relation to the planes defined by the gates 16 that when the gates 16 are moved into closed position, as shown at 16b of Fig. 2, the arms 24 will lie substantially parallel to the frame member 22.

As shown in Figs. 3 and 4, the latch means 23 comprises an electromagnet 27 having at one end thereof a split clamp 28 whereby it may be secured to the frame member 22. At the forward or leftward portion of the electro-magnet 27 there are brackets 26 carrying a horizontal hinge pin 29 to swingably support a keeper or armature 30 which forms part of an engagement member 31 of the gate latching mechanism. When the electro-magnet 27 is energized, the engagement member 31 will be held in a substantially horizontal plane and when the electro-magnet 27 is de-energized, the weight of the armature 30 will swing it into the released position indicated by dotted lines 31'. The engagement member 31 is characterized by yieldability by providing thereon yieldable latch dogs 32 which are formed by the lower portions of substantially triangular plates 33 swingable on opposite sides of the forward or leftward end of the member 31 on pins 34, there being stop pins 35 projecting from the sides of the member 31 into slots in the members 33 to limit the upward and downward movement of the latch dogs 32.

The ends of the arms 24 have thereon engagement members 36 positioned so that when the gates 16 are swung into closed position, the engagement members 36 will be moved in under the leftward portion of the engagement member 31, lifting the yieldable latch dogs 32 and passing there beyond so that these latch dogs 32 may drop into the positions in which they are shown in full lines in Fig. 3 to engage the front shoulders of the engagement members 36, it being understood that previously to these acts, the electro-magnet 27 has been energized so that the engagement members 31 are thereby held in horizontal position by the magnetic flux acting within the armature 30.

The leftward force exerted by the engagement member 36 against the latch dog 32 tends to rotate the engagement member 31 in clockwise direction, but such rotation is prevented by the holding power of the electro-magnet 27. However, should a horse in a stall exert an excessive force against the associated gates 16, the force applied through the engagement member 36 to the dog 32 will rotate the engagement member 31 against the holding force of the electro-magnet 27, rotating the member 31 into its dotted line position 31' and permitting the engagement member 36 to pass leftwardly from engagement with the latch shoulders of the engagement member 31 provided by the dogs 32. In the normal operation of the starting gate device, the electro-magnets 27 are included in a single energizing circuit, and when this circuit is interrupted, all 75 of the electro-magnets 27 will be simultaneously

deenergized, so that the engagement members 31 will simultaneously swing into released position 31' and the gates 16 may be then swung by their associated springs 37, Fig. 1 into opened position.

As previously mentioned herein, it is customary to energize the electro-magnet 27 prior to the closing of any of the gates 16. Should this energization of the electro-magnet 27 fail to move any engagement member 31 to latching position, the movement of one of the arms 24 toward the position thereof shown in full lines in Figs. 3 and 4 will bring the associated end portion 38 thereof into engagement with a finger or plate 39 which projects outwardly from the engagement member 31, thereby moving the member 39 in rightward direction so as to swing the armature 30 further into the magnetic field of the electro-magnet 27, so that the magnetism may then act to draw the armature 30 against the lower face of the electro-magnet 27.

In Fig. 5 I show the upper portion of gates 40 in closed position, with the meeting edge bars 41 thereof in engagement as shown also in Fig. 7. One of the gates 40 has a bar 42 extending rearward therefrom, this bar 42 being braced by the member 43, if desired. To cooperate with the gate 40 through the use of the bar 42, latch means 44 are provided, such latch means consisting, as shown in Fig. 6, of an engagement member 45 supported by means of a pivot 46 on the extremity of the bar 42 and an engagement member 47 pivotally supported on the frame member 22 of the structure 11 by means of a bracket 48, which bracket 48 likewise carries an electro-magnet 49 for cooperation with a keeper or armature 50 which projects upwardly across the front face of the electro-magnet 49 at the rearward portion of the engagement member 47.

In this form of the invention the magnetically held engagement member 47 has a latching shoulder 51 which is rigidly held in position when the electro-magnet 49 is energized. The engagement member 45 is yieldable so that as the end of the bar 42 moves toward the position in which it is shown, Fig. 6, the forward end of the engagement member 45 will ride over and pass by the forward portion of the engagement member 47 to bring the latching shoulder 52 thereof into cooperative relation with the latching shoulder 51, as shown.

As shown in Figs. 5 and 7, the vertical member 41 of the gate 40 cooperating with the latch means 44 has thereon a locking plate or member 53 for the remaining gate 40. This member 53 has therein a notch 54 to receive the end 55 of the member 56 mounted on the other gate 40. The members 53 and 56 may be secured in the position shown by use of welds 57. The operation of the gate is preferably connected as follows: The right hand gate 40 is first swung in the diagonal or closed position in which it is shown in Figs. 5 and 7, and the left hand gate 40 is swung inward to bring the members 53 and 56 into adjacent relation with each other and to carry the latching element 45 into latching engagement with an engagement member 47 held in operative position by the magnetic flux of the energized electro-magnet 49. The right hand gate 40 will be held in closed position by the locking or holding means of the left hand gate 40 represented by the notched plate 53.

When the electro-magnet 49 is deenergized, the engagement member 47 will rotate in anti-clockwise direction into the position thereof shown by dotted lines 47', removing the latching

shoulder 51 thereof from engagement with the latching shoulder 52, thereby releasing the gates 40. It will be noticed that the latching shoulders, Fig. 6, are disclosed in a horizontal plane above the pivot pin 58 on which the engagement member 47 is swung. Accordingly, outward force exerted through the engagement member 45 tends to rotate the engagement member 47 into releasing position, which may occur should an excessive force be exerted against the gate means held by the latch means 44.

In the foregoing we have described a form of invention wherein the non-sticking latch means is employed to connect gates to stationary parts of the structure 11. In Fig. 8 we show the manner in which the cooperating engagement members of the latching device may be mounted upon the cooperating gates of a stall 13 so as to hold the meeting edges 17 thereof together. In this form of the invention we have shown latch means comprising an engagement member 59 supported by means of a plate 60 in such position relative to the meeting edges 17 of the gates as to cooperate with an engagement member 61 carried by a plate 62 supported on the other gate. The engagement member 61 is swingable on a pivot 63 and comprises an armature 64 lying on one side of the pivot 63 and a hook portion 65 on the side of the pivot 63, an electro-magnet 66 being employed to releasably hold the armature 64 and to thereby releasably maintain the latch member 61 in operative position.

The engagement member 59 is supported by a pin 67 so that it may yield downwardly against the action of a leaf spring 68 to permit the hooked forward end 69 thereof to pass the hooked portion 65 of the engagement member 61, when the gates 16 are swung so as to bring the meeting edges 17 thereof into engagement. Release of this latch means is likewise accomplished by merely deenergizing the electro-magnet 66 so that the armature 64 may swing downward, thereby raising the hooked portion 65 out of engagement with the hooked end 69 of the member 59.

It is to be understood that the electrical circuit arrangements may be similar to that shown in Figure 5 of our Patent No. 2,309,952, patented February 2, 1943, as such circuits are now in common use for starting gates, and as shown by other prior art patents such as Puett et al. No. 2,232,675, patented February 18, 1941, and now Reissue Patent No. 22,203, patented October 13, 1942.

The following are features of the present structure:

- (1) The armature 30 is mounted on the framework and said armature swings in a vertical plane.
- (2) The armature is substantially horizontal when held by the magnet, see full line position of said armature in Figure 3.
- (3) The armature swings by gravity when released by the magnet and assumes an inclined position as shown in dotted lines in Figure 3.
- (4) The arm means or structural part 24 is rigidly mounted with regard to the door, and is mounted on the pivot of the door.
- (5) Each arm means has a free end with a surface adapted to be contacted by a corresponding surface of the armature, to hold said arm means and because of its rigid relation with the door, said door in closed position.
- (6) As seen in Figure 3 the armature is provided with a surface on the part 32 which is part

of the armature that engages the surface on the part 36 which forms part of the end of the arm means 24.

(7) The arm means of each door extends substantially in a horizontal direction.

(8) The arm means extends substantially parallel with the longitudinal axis of the gate and transverse to the partitions when its door is in closed position.

(9) The armature of each gate swings in a vertical plane that is substantially transverse to the longitudinal axis of the gate and substantially parallel to the partitions.

(10) The front face 101 of the gate is defined substantially by a plane passing through the vertical supports 100 and the horizontal support or lateral frame member 22. It will be noted that this face 101 is parallel to the longitudinal axis of the gate as seen in Figure 2.

By longitudinal axis is meant a line extending from the front wheel supporting axle to the rear wheel supporting axle.

We claim as our invention:

1. In a race starting gate, the combination of: a pair of gates pivotally supported at the forward part of said starting gate, said gates being swingable from a closed position in which said gates are angularly positioned with respect to each other and with their outer ends adjacent to each other to an open position in which said gates are in substantial parallelism; latch means for releasably latching said gates in closed position, said latch means including a latch element on one gate, a latch lever engageable with said latch element but movable to release said latch element, said latch lever and latch element comprising a pair of latching members including a plurality of pivoted parts, one of said members being provided with yieldable means whereby upon contact of one member with the other member during movement of said gates to closed position, said yieldable means permits movement of one of said members relative to the other to allow said members to move past each other, magnetic means for holding said latch lever in latching engagement with said latch element, whereby upon deenergization of said magnetic means said magnetic means said magnetic means will allow said latch lever to release said latch element for permitting said gates to open, and means for moving said gates to open position.

2. In a race starting gate, the combination of: a pair of gates pivotally supported at the forward part of said starting gate, said gates being swingable from a closed position in which said gates are angularly positioned with respect to each other and with their outer ends adjacent to each other to an open position in which said gates are in substantial parallelism; latch means for releasably latching said gates in closed position, said latch means including a latch element on one gate, a latch lever on the other gate engageable with said latch element but movable to release said latch element, said latch lever and latch element comprising a pair of latching members, said latch element and said latch lever being pivotally mounted, one of said members being provided with yieldable means whereby upon contact of one member with the other member during movement of said gates to closed position, said yieldable means permits movement of one of said members relative to the other to allow said members to move past each other, magnetic means on said other gate for holding said latch lever in latching engagement with

said latch element, whereby upon deenergization of said magnetic means said magnetic means will allow said latch lever to release said latch element for permitting said gates to open, and means for moving said gates to open position.

3. In a race starting gate, the combination of: a pair of gates pivotally supported at the forward part of said starting gate, said gates being swingable from a closed position in which said gates are angularly positioned with respect to each other and with their outer ends adjacent to each other to an open position in which said gates are in substantial parallelism; latch means for releasably latching said gates in closed position, said latch means including a latch element on one gate, a latch lever engageable with said latch element but movable to release said latch element, said latch lever and latch element comprising a pair of latching members, said latch lever being pivotally mounted, one of said members being provided with yieldable means whereby upon contact of one member with the other member during movement of said gates to closed position, said yieldable means permits movement of one of said members relative to the other to allow said members to move past each other, magnetic means mounted on a stationary part of said starting gate and supporting said latch lever for holding said latch lever in latching engagement with said latch element, whereby upon deenergization of said magnetic means said magnetic means will allow said latch lever to release said latch element for permitting said gates to open, and means for moving said gates to open position.

4. In a race starting gate, the combination of: a pair of gates pivotally supported at the forward part of said starting gate, said gates being swingable from a closed position in which said gates are angularly positioned with respect to each other to an open position in which said gates are in substantial parallelism, latch means for releasably latching said gates in closed position, said latch means including a pivoted latch element on one gate, a latch lever pivotally mounted on the other gate and having a part engageable with said latch element, said latch lever also having an armature, said latch lever being movable to release said latch element, said latch element and latch lever comprising a pair of latching members, one of said members being provided with yieldable means whereby upon contact of one member with the other member during movement of said gates to closed position, said yieldable means permits movement of one of said members relative to the other to allow said members to move past each other, magnetic means on the same gate as said latch lever and located adjacent to said armature for magnetically attracting said armature for holding said latch lever in latching engagement with said latch element, and whereby upon deenergization of said magnet means, said latch lever will release said latch element for permitting said gates to open, and means for moving said gates to open position.

5. A starting gate having a superstructure including a plurality of partitions, a pair of doors between two adjacent partitions, said doors having pivot means and being swingable from a closed position wherein the side edges of said pair of doors farthest from said pivot means are adjacent to each other, to an open position where the doors are substantially parallel to each other, arm means on one door having a free end there- of spaced rearwardly from the adjacent edges

and spaced horizontally to one side of said pivot means, latch means for releasably latching said doors in closed position, said latch means including a latch element on said arm means at its free end, a solenoid provided with an armature, means attaching said solenoid including said armature directly to a stationary part of said superstructure, said means including means pivotally mounting said armature, said armature being heavier on one side of said pivot than on the other side thereof and being biased to released position by gravity, and said armature having means including a surface contacting said latch element at the free end of said arm means, said solenoid when energized and with said doors in closed position serving to hold said armature and said latch element, and when deenergized releasing said armature whereby said armature moves by gravity to released position, thereby releasing one of said doors.

6. A starting gate having a framework including a plurality of partitions, a pair of doors between two adjacent partitions, said doors having pivot means and being swingable from a closed position wherein the side edges of said pair of doors farthest from said pivot means are adjacent to each other, to an open position where the doors are substantially parallel to each other, arm means on one door having a free end, means attaching said arm means only to said door pivot means whereby said arm means extends substantially parallel with the longitudinal axis of the gate and transverse to said partitions when the door is in closed position, latch means for releasably latching said doors in closed position including: a solenoid provided with an armature, means attaching said solenoid including said armature directly to said framework, said means including means pivotally mounting said armature, said armature being heavier on one side of said pivot than on the other side and being thus biased to released position by gravity, the free end of said arm means having a latching surface and said armature having means including a latching surface adapted to contact said surface first named, said solenoid when energized and with said door in closed position serving to hold said armature, with said armature surface in contact with said arm surface for holding said door in closed position and when deenergized releasing said armature whereby said armature moves by gravity to released position thereby releasing said arm surface and said door, whereby said door may be moved to its open position.

7. A starting gate having a framework including a plurality of partitions, a pair of doors between two adjacent partitions, said doors having pivot means and being swingable from a closed position wherein the side edges of said pair of doors farthest from said pivot means are adjacent to each other, to an open position where the doors are substantially parallel to each other, arm means on one door having a free end, means attaching said arm means only to said door pivot means whereby said arm means extends substantially parallel with the longitudinal axis of the gate and transverse to said partitions when the door is in closed position, latch means for releasably latching said doors in closed position including: a solenoid provided with an armature, means attaching said solenoid including said armature directly to said framework, said means including means pivotally mounting said armature, whereby said armature swings in a vertical plane that is substantially transverse to the lon-

5 gitudinal axis of the gate, said armature being heavier on one side of said pivot than on the other side and being thus biased to released position by gravity, the free end of said arm means having a latching surface and said armature having means including a latching surface adapted to contact said surface first named, said solenoid when energized and with said door in closed position serving to hold said armature, with said armature surface in contact with said arm surface for holding said door in closed position and when deenergized releasing said armature whereby said armature moves by gravity to released position thereby releasing said arm surface and said door, whereby said door may be moved to its open position.

8. A starting gate having a framework including a plurality of partitions, a pair of doors between two adjacent partitions, said doors having pivot means and being swingable from a closed position wherein the side edges of said pair of doors farthest from said pivot means are adjacent to each other, to an open position where the doors are substantially parallel to each other, arm means on one door having a free end, means attaching said arm means only to said door pivot means whereby said arm means extends substantially parallel with the longitudinal axis of the gate and transverse to said partitions when the door is in closed position, latch means for releasably latching said doors in closed positions including: a solenoid provided with an armature, means attaching said solenoid including said armature directly to said framework, said means including means pivotally mounting said armature, said armature being heavier on one side of said pivot than on the other side and being thus biased to released position by gravity, the free end of said arm means having a latching surface and said armature having means including a latching surface adapted to contact said surface first named, said solenoid when energized and with said door in closed position serving to hold said armature, with said armature surface in contact with said arm surface for holding said door in closed position and when deenergized releasing said armature whereby said armature moves by gravity to released position thereby releasing said arm surface and said door, whereby said door may be moved to its open position, said arm means of each pair of doors extending in a straight line that is parallel to the longitudinal axis of the gate when said pair of doors is in closed position.

9. A starting gate having a framework including a pair of partitions, a pair of doors between two adjacent partitions, said doors having pivot means and being swingable from a closed position wherein the edges of said pair of doors farthest from said pivot means are adjacent to each other to an open position where the doors are substantially parallel to each other, arm means on each door each of said arm means having a free end, means attaching said arm means only to said door pivot means, latch means for releasably latching said doors in closed position including: solenoid means provided with armature means, means attaching said solenoid means including said armature means directly to said framework, said attaching means including means pivotally mounting said armature means, said armature means being heavier on one side of said pivot means than on the other side thereof and being thus biased to released position by gravity, and said armature means having means including a surface, the free end of at least one of said arm

11

means having a surface adapted to be engaged by the surface of said armature when said pair of doors is in closed position, said solenoid means when energized and with said doors in closed position serving to hold said armature means, and when deenergized releasing said armature means whereby said armature means moves by gravity to released position thereby releasing the arm means and its door.

10. A starting gate having a framework including a plurality of partitions, said framework having a front face extending along the longitudinal axis of the gate and parallel thereto, a pair of doors between each two adjacent partitions, said doors of each pair having pivot means and being swingable from a closed position wherein the side edges of said pair of doors farthest from said pivot means are adjacent to each other, to an open position where the doors are substantially parallel to each other, arm means on one door of each pair, said arm means having a free end, means attaching said arm means to said door pivot means only whereby said arm means extends substantially parallel with the longitudinal axis of the gate and transverse to said partitions when the door is in closed position, latch means for releasably latching said doors in closed position including: a solenoid provided with an armature, means attaching said solenoid including said armature directly to said framework, the said armatures and solenoids of all of said doors being mounted on a line which is at least parallel to the front face of the gate and which extends no further rearwardly than the front face of the gate, said means including means pivotally mounting said armature of each solenoid, said armature being heavier on one side of said pivot than on the other side and being thus biased to released position by gravity, the free end of said arm means having a latching surface and said armature having means including a latching surface adapted to contact said surface first named, said solenoid when energized and with said door in closed position serving to hold said armature, with said armature surface in contact with said arm surface for holding said door in closed position and when deenergized releasing said armature whereby said armature moves by gravity to released position thereby releasing said arm surface and said door, whereby said door may be moved to its open position.

11. A starting gate having a framework including a plurality of partitions, said framework having a front face extending along the longitudinal axis of the gate and parallel thereto, a plurality of pairs of doors, each pair of doors being adapted when closed, to close the space between two adjacent partitions, said doors having pivot means and being swingable from a closed position wherein the side edges of said pairs of doors farthest

5 15 20 25 30 35 40 45 50 55

12

from said pivot means are adjacent to each other, to an open position where the doors are substantially parallel to each other, arm means on said doors, said arm means having free ends and each of said arm means having an armature contacting surface adjacent its free end, latch means, said arm means and latching surface forming part of said latch means, said latch means further including: a plurality of solenoids provided with armatures, means attaching said solenoids including said armatures directly to said framework, said solenoids being mounted on a line which is at least as far forward as said front face of said gate, said attaching means including means pivotally mounting said armatures, said armatures being heavier on one side of said pivot means than on the other side thereof and being thus biased to released position by gravity, and said latching means further including said armatures and surfaces thereon adapted to engage said surfaces on said arm means, said solenoids when energized and with said pairs of doors in closed position serving to hold the surfaces of said armatures in contact with the surfaces of said arm means, and when deenergized releasing said armatures whereby said armatures move by gravity to released position thereby releasing said pairs of doors.
